UNITED STATES PATENT OFFICE

ALLEN B. COOKE, OF DANVILLE, ILLINOIS, ASSIGNOR TO UNITED AUTOGRAPHIC REGISTER COMPANY, OF CHICAGO, ILLINOIS, A CORPORATION OF ILLINOIS

AUTOGRAPHIC REGISTER

Application filed September 14, 1926. Serial No. 135,451.

My present invention relates to web feeding, severing, filing and discharging mechanism, and particularly as it appertains to structures known as autographic registers.

5 Specifically stated, my improvements have to do with registers that employ a plurality of webs or strips of paper that are adapted to be automatically severed into tickets or sets of tickets. If desired, any or all of 10 the severed tickets may be filed in a storage chamber within the register casing, or any or all of the severed tickets may be suitably discharged from the register. The present invention, while preferably employing certain features described and claimed in my 15 Patent #1,723,766 dated August 6, 1929, embodies novel elements and a novel organization of elements, whereby original record slips are filed, face down, in stacked relation and copies (duplicate, triplicate, etc.) are diverted through a lateral opening in the casing, provision being made for tearing off the laterally delivered copy or copies, one of 20 which may be given to the customer, if desired.

It has heretofore been proposed to sever tickets from the lowermost of the strips and file them in a storage chamber or compartment in the forward or discharge end 25 of the register, while the remaining upper ticket or tickets are fed out of the casing where they may be readily grasped by the operator and torn from the strips, to be distributed in the desired manner. This practice makes it possible for the upper-most ticket, which is the original, to be handed to the customer and the proprietor will not 30 therefore be able to retain this original entry unless great care is exercised by the persons operating the register. Also, as the filed tickets are taken from the lowermost strip, it is not possible to examine the same from time to time to ascertain if the manifold sheets are producing clear copies upon 35 the lower strip.

With my present preferred structure, I 40 cut off and file the tickets from the uppermost or original strip thereby retaining for the proprietor the original entry, and the other tickets from the strips below the top

are discharged in a convenient manner so as to be readily grasped by the operator and distributed according to the practice of the establishment in which the register is installed, which permits the operator to readily examine the lowermost tickets from time to time and will always be able to note the clearness with which the manifold copies are produced. In this latter connection, I have arranged the structure of the register 55 in a novel manner so that the manifold ticket strips are positively divided from the original ticket strip and are discharged laterally through an opening in the sidewall of the register casing within convenient 60 reach of the operator who may grasp their ends and by a slight pull laterally from the side of the casing detach the tickets from their respective strips. 65

My invention has numerous objects in view, among which are the provision of an autographic register that is novel in the form and arrangement of the parts, simple in construction, dependable in performing the several functions for which it has been 70 designed, and which is economical to manufacture. I prefer to carry out my invention and to accomplish the divers objects thereof in substantially the manner hereinafter 75 fully described and as more particularly 80 pointed out in the claims, reference being herein made to the accompanying drawings that form a part of this specification.

In the drawings:—

Figure 1 is a vertical elevation of a portion of the operating side of my improved 85 register.

Figure 2 is a vertical longitudinal section thereof taken on the irregular line 2—2 of Figure 3. 90

Figure 3 is a top plan of the portion of the structure illustrated in Figure 1, parts of the cover being omitted for clearness.

Figure 4 is a transverse vertical section taken on the irregular line 4—4 Figure 2. 95

Figure 5 is a fragmentary diagram of the elements in the upper portion of Figure 2 showing the same in advanced positions in the cycle of operation.

Figure 6 is a view of the elements illus- 100

trated in Figure 5 in still further advanced positions and just after the original or top strip has been severed by the cutting blade.

Figure 7 is a plan of a blank form or strip such as used in this apparatus.

The drawings are, in a sense, merely schematic for the purpose of illustrating a preferred or typical embodiment of my invention, and in said drawings, I have employed similar reference characters to designate the same parts wherever they appear throughout the several views.

For the purpose of convenience the portion of the casing adjacent the operator will be herein designated the back or rear portion, while that towards the customer will be designated the front. The casing of the register is of the type usual in autographic registers, consisting of vertical longitudinal side-walls 10 arising from a base or bottom plate 11, and are connected along a portion of their upper edges by a writing bed plate or platen 12. The feed and control mechanism is located forward of the center of length of the casing with the platen extending towards the rear and partly covered by a margin plate 13 that has an enlarged central opening through which the tickets are exposed and may be written upon, and the paper strips are stored in rolls 14 upon suitable hubs in the space below the platen. Forward of the feed and control mechanism there is an enclosed storage space or compartment 15, into which the top or original tickets are advanced and impaled upon suitable filing pins 16. The filing pins may be operated in any suitable manner such as disclosed in my prior application and need not be described herein, and the webs of paper each consists of a strip 17 (Fig. 7) that is provided with spaced rows of longitudinal apertures or punched-holes 18 that are located in pairs between the respective tickets printed on the strip and are utilized in the control of the strip advancement and registration of the tickets as well as for filing purposes.

The strip-feeding mechanism preferably consists of upper and lower feed roller shafts 19 and 20 the former of which is journaled in a lift frame 21 hinged at one end to ears 22 at the side of the casing to permit the same to be raised when inserting the paper strips, and the lower shaft is journaled in the side walls of the casing in vertical alinement below the shaft 19. Forward of these shafts is the drive-shaft 23 that extends through bearings in the side-walls of the casing and has an operating handle or crank 24 secured to its end that is in front of the hinge of the lift-frame 21. The opposite end of the drive-shaft 23 has a gear 25 secured to it that meshes with an intermediate idle gear 26 carried on a stud

projecting from the side-wall 10, and said idle gear is in mesh with and drives a pinion 27 upon the adjacent extended end of the lower feed roller shaft 20 and the proportions of this gearing is such that the feed-roller shaft 20 is rotated faster than the drive-shaft 23. Shafts 19 and 20 are parts of the upper and lower feed members that advance the strips through the register, and are geared together at their ends opposite the pinion 27, by the respective gears 28 and 29, the former of which is smaller than the latter so that the upper shaft 19 travels at a higher speed and rotates a greater number of times than the lower shaft 20. Upper and lower opposed feed roller members 30 and 31 in the form of disks are secured to the respective shafts 19 and 20 and are spaced apart upon said shafts the distance between the pairs of apertures 18 in the paper strips, and said feed roller members are of less thickness than the diameter of the apertures so that when the latter come into registration with said members the advance of the strips will be arrested. The arrest of the strip advancement takes place intermittently or at the end of each set of tickets fed through the register and will be noted that the upper and lower feed roller members are of different diameters in the same ratio as the diameter of the gears 28 and 29 so that there is a dependable feed of the strips when the disks are not in registry with the filling apertures of the strips. When the respective feed members are registered with the apertures they are inoperative to advance the strips until the latter have been advanced slightly by the starter or initial feed devices. Any suitable starter devices may be employed, and for convenience I have shown the type of mechanism which is the subject-matter of my co-pending companion application which is executed and filed even date herewith. This structure, briefly stated consists of radial lugs, blocks, or projections 32 and 33 that extend from the respective feed shafts 19 and 20, and have concentric outer faces of the same radial diameters as the feed roller members 30 and 31. The rotation of the feed shafts 19 and 20 are timed so that the respective elements 32 and 33 oppose each other but once in a plurality of revolutions which is at about the time the feed rollers register with the filing apertures in the strips,—in other words, shaft 19, in the illustration given, revolves eight times to five revolutions of shaft 20. The driving mechanism is also controlled so as to be stopped at the time the peripheries of the elements 32 and 33 come into engagement. This is done by a cam stop 34 on the end of a driven cam shaft 35 extended through the walls of the casing, which stop is engaged by a projection 36 on a spring-returnable bell-crank trigger 37.

that is pivotally carried by the crank-handle 24. The opposite end of cam shaft has a gear 38 secured to it that is in mesh and is driven by a pinion 39 next to gear 25 on the drive-shaft 23 so that the idle cam shaft 35 makes a single revolution during two revolutions of drive-shaft 23, and then the cam is in position to stop the rotation of the crank.

In front of the feed roller members there is mounted a horizontally disposed divider element in the form of a bar 40 of irregular section with its horizontal portion, which is nearest the feed members, tapered to a somewhat pointed edge 41 that faces the strips being advanced by the feed mechanism. The bar extends transversely from wall to wall of the register and its upper surface is in the same horizontal plane as the platen so that when the strips are inserted and feed through the apparatus the upper or original strip will pass over the upper surface and into the filing space 15 of the register, while the remaining strips are separated from the upper strip and pass downwardly against the inclined face of the bar. It will be understood that more than one strip may be fed into and stored in the filing space and I do not limit myself to the filing of only the original or upper strip. Extending forwardly and downwardly from the front end of the platen 12 is an inclined guide plate 42 the forward edge of which is sharpened in to a beveled tearing-blade 43 spaced slightly from the bar as seen in Figure 2 so that the tickets to be discharged and removed may be pulled against said blade and thus detached from the strip or strips. The lower strips travel between the guide plate and the bar and pass into a conical or horn-shaped discharge chute or receptacle 44 the walls of which taper (converge) towards the casing wall opposite the operating handle 24. The strip or strips are discharged into this chute until their advance has been arrested in the manner above described and it will be found that a corner α of the discharged strips will have been projected beyond the plane of the side-wall of the casing where it may be readily grasped by the operator and pulled horizontally away from the register and out of the chute and the slight twist or curl of the strips in this operation is sufficient to cause the strips to be pulled against the blade 43 and the tickets torn from the respective strips. The wide or larger end of the chute fits an opening or window 45 in the adjacent side-wall of the casing, and its opposite end is provided with lugs 46 by which the same is secured to the adjacent other wall of the casing.

Mechanism is provided to detach from the strip or strips the tickets to be filed upon the pins 16 in the forward or filing cham-

ber of the register, and this is preferably in the form of a clamping mechanism to hold the strip or strips, and a knife to sever the tickets, together with actuating mechanism that is synchronized with the driving of the feed devices, so as to operate when the advance of the paper has been arrested. The upper portions of the side-walls 10 are provided with vertically elongated slots 47 in which are guided the ends of horizontal clamping-bars 48 and 49 that consist of elongated metal plates positioned upon their edges and having ears 50 projecting from their ends outside the walls of the casing to which the upper ends of coiled contraction springs 51 are connected for urging said bars normally down toward the divider bar 40. The faces of the clamping bars are close to each other, being spaced apart only far enough for the interpositioning of a thin cutter-blade or knife 52, and said bars are mechanically moved downwardly so that their lower longitudinal edges will contact the divider bar 40 or the paper strips thereon and hold the latter firmly while the knife is being operated to sever the ticket or tickets. The upper surface of the bar is provided with a narrow groove 53 at the location where the knife will engage the same to cut the paper, and said knife and the clamping bars are reciprocated vertically by means of a cam and bell-crank structure.

The cam-shaft 35 is provided near its ends with cam 54 that have portions that are concentric with their axes of rotation and other portions that are irregular in form, and the edges of said cams are engaged by rollers 55 carried upon the lower arms 56 of a pair of three-arm bell-cranks secured to a horizontal rocker-shaft 57. Upper arms 58 project in the same direction from the bell-crank as the lower arms 56 and have straight edges 59 that are engaged by crank-pins 60 projecting from the faces of the cams 55. The third arms 61 of the bell-crank project in the opposite direction away from the upper and lower arms 56 and 58 and their end portions are engaged with the clamping bars and the knife to actuate the same. Clamping-bars 48 and 49 are respectively provided with vertically elongated slots 62 and 63, of sufficient width to be entered by the arms 61, and it will be seen that the slots in the clamping bar 49 are slightly longer than those in the other clamping bar 48. Apertures 64 are made in the knife 52 which are just the size to receive the arm 61 of the bell-crank without permitting any play between these parts. When the clamps and knife are raised to normal position during the advancement of the strips through the register the upper end edges of the slots 62 and 63 and the upper edges of the apertures 64 in the knife are all in alinement as shown in Figure 2 with

the crank-pins 60 out of engagement with the arm 58 and with the rollers 55 on the lower arms 56 engaging the concentric portions of the cams 55^a, which are rotating in the direction of the arrows in Figures 5 and 6. As soon as the eccentric portions of the cams engage with the roller 55 (just prior to reaching the position shown in Figure 5) the bell-cranks will rock thus lowering the arms 61 permitting the spring 51 to pull down the clamping-bars into engagement with the paper prior to the cutting action by the knife. The crank-pins 60 now engage the straight portions of arms 58 to raise the latter and cause a quick downward movement of the ends of the arms 61 that are engaged with the knife, which forces the knife through the paper into the slot 53 on the upper surface of the divider bar thus severing the ticket or tickets from the strip or strips that are to be filed. The cam shaft 35 continues to rotate until the stop-cam 34 arrests the further rotation of the operating crank-handle 24 and as the crank-pins 60 clear the arms 58 the rollers 55 begin to move towards the concentric portions of the cams 55^a, which movement depresses the arms 56 and raises the arms 61 so that first the knife is withdrawn, then the clamping bar 48 is raised (which releases the cut-off portion of the paper to be filed), and lastly the clamping bar 49 is raised from the adjacent end of the strip or strips so that the advancement of the paper may be accomplished without interference when the next set of tickets is to be fed through the machine. In order to guide the paper to the filing pins 16 prior to being severed by the knife, there is provided a movable guard in the form of a horizontally disposed concavo-convex plate 65 the upper corners of which are provided with lateral trunnions 66 that enter small apertures in the side-walls of the casing and hingedly mount the guard in a position so that the paper will readily pass between its concave side and the curved or convex face of the divider-bar 40.

It will be appreciated that, while I have herein described a structure in which the top or original strip is adapted to be cut into tickets and filed in the storage space at the front of the register and the remaining tickets advanced through the side of the register to be grasped and torn off, more than one of the strips may be fed into the forward storage space and cut and filed upon the pins, and such use is fully contemplated as coming within the scope of the appended claims.

It will be understood from Fig. 2 that during the feeding operation the uppermost strip is deflected downwardly into the filing compartment 10 by means of the member 65. The filing pins 16 are actuated in any suitable manner, as, for example, in the manner

described in my pending application Serial No. 46,714, filed July 29, 1925. In the operation, the front end of the strip is deflected downwardly while the filing pins are retracted; and at the proper time the filing pins are advanced into contact with the paper so as to be into position to move into engagement with the apertures with which the slip is provided at its front end. Eventually, the ticket, or sales slip, is severed from the strip and the slip is deposited face downward in the filing compartment in the manner fully explained in the application just referred to.

Also, during the feeding operation, the copy-strips (duplicate, triplicate, etc.) are deflected downwardly by the member (divider) 40 into the conical compartment 44 which opens laterally through one lateral wall of the casing; and these copy-strips are so curled beneath the tearing-off edge 42 as to be readily accessible at the discharge orifice of the chamber 44. At the conclusion of the feeding operation, the main feed-disks operate idly when they encounter the apertures in the strips. The crank is turned, however, until the driving-means is automatically arrested by the stop-arm 34 on the rotating stop-shaft 35. This occurs at the instant that the initial-feed segments 32 and 33 come into their initial gripping relation and grip the strips. The segments are thus in position to hold the strips while the copy-strips are being severed on the tearing-edge 42 by a pull on the strips in a lateral direction with respect to the casing. Also, the segments are thus left in position to be in readiness to initiate the feed at the next feeding operation.

The feed-mechanism illustrated and described is peculiarly useful in connection with the present machine, since it is important that the strips be gripped or positively held during the operation of tearing off the copy-tickets.

By filing the original sales slips 17 in inverted condition, they are stacked in the sequence of issuance, and the stack of slips may be retained in this order when it is removed from the filing compartment to enable the slips to be permanently filed.

The foregoing detailed description has been given for clearness of understanding only, and no unnecessary limitations should be understood therefrom, but the appended claims should be construed as broadly as permissible, in view of the prior art.

What I claim is:

1. In an autographic register a casing including a platen, there being an opening in a side-wall of said casing, devices for feeding a paper strip across said platen, and a conical chute positioned in said casing opening into which the strip is fed and from which

the same is withdrawn laterally to the side-wall of the casing.

2. In an autographic register a casing including a platen, one of the side-walls of the casing provided with an opening, devices for feeding a paper strip across the platen, a transverse severing edge over which the fed strip is disposed, and a conical chute positioned in said casing opening adjacent said severing edge into which the strip is fed and from which the strip is withdrawn and detached upon said severing edge.

3. In an autographic register, a casing including a platen, there being an opening in a side-wall of said casing, devices for feeding a plurality of paper strips across said platen, means for separating at least the upper strip from the remaining strips and discharging the same into a storage chamber, and a conical chute positioned in said casing opening into which the said remaining strip or strips is fed and from which the same is withdrawn laterally to the side-wall of the casing.

4. In an autographic register, a casing including a platen, one of the side-walls of the casing provided with an opening, devices for feeding a plurality of paper strips across said platen, means for separating at least the upper strip from the remaining strip or strips and discharging the same into a storage chamber, a transverse severing edge over which said remaining strip or strips is disposed, and a conical chute positioned in said casing opening adjacent said severing edge into which the remaining strip or strips is fed and from which the same may be withdrawn and detached upon said severing edge.

5. A register of the character set forth, comprising a casing provided with a platen, strip-feeding means adapted to feed a plurality of superimposed strips over and project them beyond said platen, means for severing and storing at least the uppermost of said strips, means for separating and diverting laterally the remaining strip or strips, and means for severing the diverted strip or strips.

6. A register of the character set forth, comprising a casing provided with a platen and equipped adjacent the rear portion of the platen with strip-feeding means and below the latter with a strip-diverting device having an orifice opening through one side of the casing, a storage-chamber back of said device, a divider over which one or more strips pass to said storage-chamber and beneath which the other strip or strips pass to said diverting device, and means for effecting severance of both sets of strips.

7. A register of the character set forth, comprising a casing provided with a platen and equipped adjacent the rear portion of the platen with strip-feeding means and be-

low the latter with a strip-diverting device having an orifice opening through one side of the casing, a storage-chamber back of said device, a divider over which one or more strips pass to said storage-chamber and beneath which the other strip or strips pass to said diverting device, a depressible cutter above the path of the uppermost strip, means for actuating said cutter, and a stationary tear-off edge beneath the path of the lower strip or strips.

8. In a register of the character set forth, a casing provided with a platen and having a lateral opening through which copy-strips may be drawn, strip-feeding mechanism near the rear end of said platen provided with means for feeding the strips a predetermined distance and then working idly and provided with means for gripping the strips after the conclusion of the feeding operation, a filing compartment in the rear of the strip-feeding means, a divider over which at least the uppermost strip is fed to said filing compartment and beneath which the remaining strip or strips are deflected downwardly, a tearing-edge spaced below said divider upon which the copy-strips may be severed by pulling said strips while they are gripped by said strip-feeding means at the end of the cycle of operations, a cutter adapted to sever the strip or strips passing over said divider, and cutter-operating means actuated by the feeding mechanism.

9. In a register of the character set forth, the combination of a casing provided with a platen and having a lateral delivery orifice, strip-feeding mechanism comprising a pair of shafts equipped with main feed-disks and equipped also with initial-feed segments, gear connections between said shafts whereby the shafts will rotate at different speeds, said main feed-disks being adapted to work idly when they encounter apertures in the strips and said initial-feed segments being adapted to grip the strips after the conclusion of the feeding operation, a storage-compartment back of said feed-disks, a divider interposed between said feed-disks and said compartment and adapted to deflect the lower strip or strips downwardly, and a tearing edge spaced below said divider upon which the lower strips may be severed while held by said segments at the end of a cycle of operations.

10. In a register of the character set forth, the combination of a casing provided with a platen and having a lateral opening through which copy-strips are accessible, feed-mechanism comprising a pair of shafts having different speeds of rotation and equipped with main feed-disks which are adapted to work idly when apertures in the strips are encountered and equipped also with initial-feed segments, a divider and an associated shearing edge over which at least the upper-

most strip is fed, and beneath which the remaining strips are fed, means whereby slips may be severed from the lower strip or strips, a cutter disposed above said shearing edge, cutter-actuating means actuated by 5 said feed-mechanism, a compartment into which the upper strip is fed, and impaling means in said compartment.

11. In a register of the character set forth, 10 a casing having a lateral opening and equipped above said opening with a tear-off edge and above said tear-off edge with a divider for deflecting strips downwardly, and feed-mechanism comprising main feed-disks 15 adapted to work idly when they encounter apertures in the strips and associated initial-feed segments adapted to grip the strips after the conclusion of the feeding operation and hold said strips to permit them to be 20 severed by pulling them against said tearing edge.

12. A register of the character set forth, comprising a casing provided with a platen, strip-feeding means adapted to feed a plurality of strips across and beyond the platen, 25 a storage chamber back of the platen for receiving and storing at least the original strip, means for separating and diverting downwardly and directing laterally the remaining strip or strips, and means for severing the diverted strip or strips.

13. In an autographic register, a casing including a platen and a side-wall provided with an aperture, devices for feeding a paper 30 per strip across said platen, and means for delivering the strip through said aperture.

14. In an autographic register, a casing including a platen, and a side-wall having an aperture, devices for feeding a paper 35 strip across said platen, a transverse severing edge over which the fed strip is disposed, and means for delivering the strip through said aperture, whereby the strip may be pulled laterally to detach the same 45 upon said severing edge.

15. In an autographic register, a casing including a platen and a side-wall provided with an aperture, devices for feeding a plurality of paper strips across said platen, 50 means for separating at least the upper strip from the remaining strip or strips and discharging the same into a storage chamber, and means for delivering said remaining strip or strips through said aperture.

16. In an autographic register, a casing including a platen and a side-wall provided with an aperture, devices for feeding a plurality of paper strips across said platen, 55 means for separating at least the upper strip from the remaining strip or strips and discharging the same into a storage chamber, a transverse severing edge over which the said remaining strip or strips is disposed, and means for delivering said remaining 65 strips or strip through said aperture, where-

by the same may be pulled laterally to be detached upon said severing edge.

17. In an autographic register, a casing including a platen and a side-wall provided with an aperture, means for feeding a plurality of paper strips across said platen, 70 means for dividing the strips and directing them in two separated paths, means for directing the lower strip or strips laterally through said aperture, and means for detaching tickets from all of said strips. 75

18. In an autographic register, a casing including a platen and a side-wall provided with an aperture, means for feeding a plurality of paper strips across said platen, 80 and means for dividing the strips and directing them into two separated paths, one of which paths discharges its strip or strips through said aperture.

19. A register of the character set forth, 85 comprising a casing provided with a platen and having a side-wall provided with an aperture, strip-feeding means adapted to feed a plurality of strips across and beyond the platen and then to work idly, a divider 90 element for separating and diverting downwardly the lower strips to a position where they are accessible through said aperture, a cutter associated with said divider element adapted to sever the uppermost strip, 95 and cutter-actuating mechanism geared to the strip-feeding means and operating after the conclusion of the strip-feeding operation to effect severance of said uppermost strip. 100

Signed at Danville, in the county of Vermillion and State of Illinois, this 17th day of July, 1926.

ALLEN B. COOKE.
